CLAIM

The ornamental design for a communication handset, as shown and described.

DESCRIPTION

FIG. 1 is a front elevational view of a communication handset;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is a rear elevational view thereof.

The broken line showings at the bottom, FIG. 3, are for
illustrative purposes only and form no part of the claimed
design.
